UNITED STATES PATENT OFFICE.

ARVID LIND, OF STOCKHOLM, SWEDEN.

PROPELLED MECHANISM FOR BOATS.

Application filed May 15, 1923. Serial No. 639,106.

To all whom it may concern:

Be it known that I, ARVID LIND, a citizen of the Kingdom of Sweden, residing at Stockholm, Sweden, have invented new and 5 useful Improved Propelling Mechanism for Boats, of which the following is a specification.

The present invention relates to that type of propelling mechanism for motor boats 10 which comprises a suspension device adapted to be attached to the bulwark of the boat, an internal combustion engine having a substantially vertical shaft, and a screw-propeller attached to the lower end of said 15 shaft.

The object of the invention is to provide a propelling mechanism of the kind referred to which is compact and has a low weight in relation to its effect, is easily to start and 20 runs uniformly.

The invention is characterized, chiefly, by that the propelling mechanism comprises an explosion engine of the two stroke type provided with a plurality of cylinders the 25 axes of which are parallel to the engine shaft and the pistons of which are in direct engagement with a gyratorically swinging thrust disk journaled on an oblique hub secured to the engine shaft.

30 The invention is illustrated on the accompanying drawings in which, Figure 1 is a side elevation of the entire propelling mechanism; Fig. 2 is a plan view thereof; Fig. 3 is a rear end view of the mechanism with 35 the lower portion of the shaft and the screw propeller removed. Fig. 4 is a view showing the steering mechanism from the under side thereof. Fig. 5 is a vertical section on a larger scale of the engine taken along the 40 line A—B in Fig. 7. Fig. 6 shows a detail of the suspension device. Fig. 7 is a plan view of the engine with the flywheel removed.

45 Referring to the drawings the engine illustrated comprises four cylinders 1, which are uniformly distributed around the vertical, centrally arranged shaft 2 with their axes extending parallel to the shaft of the engine. Each cylinder contains a piston 3 engaged by a thrust disc 4 mounted on an oblique hub secured to the shaft 2, by means of a ball and socket joint including a perforated ball 5 on an extension of the disc and sliding blocks 6 mounted in the pistons. 50 The cylinder chamber 7 above the upper

ends of the pistons form working chambers and are provided in a way commonly used in two stroke cycle engines with ports 8 controlled by the pistons through which the charge is introduced into the said 60 chambers from a storing chamber 42 formed in the cylinder block, the cylinder chambers being also formed with ports 9 through which the expanded combustion 65 gases may pass into an annular exhaust chamber or silencer 10 surrounding the cylinder block. The cylinder chambers 11 below the lower ends of the pistons form pumping chambers 43 to enable a precompression of the charge which is drawn in 70 through a charge forming chamber not shown in the drawing and through passages formed in a slide valve attached to the shaft and rotating therewith. The design and operation of the engine proper is considered 75 not to require any further explanation, as the engine is substantially similar to that described in my copending application Ser. No. 638,889.

Provided at the lower end of the engine 80 block is a base member 12 by means of which the said block rests on an annular, downwardly tapering bracket 13 carried by the suspension device 14, by means of which the propelling mechanism is adapted to be 85 suspended at the bulwark of a boat. The lower portion of the said base member 12 forms a conical seat 15 having passages 16 leading to the cooling jacket of the cylinders. Rotatably mounted within the seat 90 15 is a cock plug 17 having passages 18 in permanent communication with the said passages 16 independent of the position of the plug. The cock plug 17 is rigidly connected to two sleeves 19 and 20 concentrically surrounding the shaft 2 and forming between themselves a passage or channel 21 to enable cooling water to pass the cooling jacket 95 of the cylinders from a pump 23 provided in connection with the hub 22 of the screw-propeller. The said sleeves 19 and 20 are also rigidly connected to the hub 22 of the screw-propeller. The screw-propeller hub surrounds in the usual way a bevel gear whereby the rotation of the engine shaft is 100 transmitted to the screw-propeller 24. At its lower end the hub 22 carries, preferably in well-known manner, a rudder 25 to facilitate steering. The steering is effected by 105 rotating the hub of the screw-propeller to- 110

gether with the screw-propeller, the two sleeves 19 and 20 surrounding the shaft 2, and the plug 17 by means of a chain wheel 26 attached to said plug and connected by 5 a chain 44 to a hand-wheel or the like 27 journaled in a bracket 28 carried by the cylinder block. At its lower end the shaft of the said hand-wheel is provided with a spring pawl 29 to hold the hand-wheel in 10 normal position. The ratio of gearing between the hand-wheel and the chain wheel 26 amounts to 2:1 thereby enabling the boat to be propelled astern by rotating the hand wheel one revolution so as to cause the hub 15 of the screw-propeller to swing half a revolution around shaft 2. A casing 30 removably attached below the fly-wheel 31 is provided to protect the sparking plugs 32 of the cylinders against water. 33 is an annular receptacle surrounding the lower portion of the cylinder block and adapted to receive the liquid fuel. 34 designates a magneto-electric generator for the ignition, said generator being driven from the shaft 2 by 20 means of a toothed gearing 35, a distributor 36 of well known design being provided secured to the shaft 2 to transmit the current from the said generator to the sparking plugs. 37 designates holding members 25 to lock the engine to the bracket 13, said members to this end being provided with handles 38 acting as cams. To obtain sufficient rigidity of the mounting of the engine in the suspension device the latter 30 is provided with a guiding ring 39 carried by depending arms 40, said ring surrounding a short sleeve or bushing 41 secured to the sleeve 20. The bracket 13 as well as the guiding ring 39 are open at their rear 35 sides to permit the engine with its shaft and the screw-propeller to be removed from the suspension device after the holding members 37 have been released and said first-mentioned parts have been lifted slightly 40 in relation to the suspension device.

While in the mechanism shown the en-

gine with its shaft and the screw-propeller may be removed from the suspension device by being lifted out thereof it may be more convenient in certain cases to divide the 50 shaft 2 so that the engine proper only may be removed, while the lower portion of the shaft together with the propeller still remains suspended in the suspension device. 55

It is evident that the invention is not limited to the details shown, as the constructional details may be varied in different ways without departing from the principle of the invention.

What I claim is:

1. Propelling mechanism for boats, comprising an internal combustion engine of the two stroke type having a vertical central shaft and a plurality of cylinders grouped around said shaft and having pistons engaged by a gyroscopically swinging thrust disc journaled on an oblique hub secured to said shaft, a screw-propeller at the lower end of said shaft, and a suspension device adapted to be secured to the bulwark of a boat, an open seat in said suspension device adapted to carry the lower end of the cylinder block, arms extending downwards from said seat, an open ring secured to said arms, a sleeve surrounding the vertical shaft, and a bushing secured to said sleeve and guided by said ring. 60 65 70 75

2. Propelling mechanism for boats, comprising an internal combustion engine of the two stroke type having a vertical central shaft and a cylinder block containing a plurality of axially extending cylinders, a cock housing at the lower end of the cylinder block, a cock plug, two concentric sleeves connected to said cock plug forming between themselves a supply channel for cooling water, and a pump for delivering cooling water through said channel and cock plug and housing to the cylinder block. 80 85

In testimony whereof I have signed my name.

ARVID LIND
